THREAD PICKING AND SEAM RIPPING
IMPLEMENT

Clara E. McNutt, Toledo, Ohio

Application July 16, 1948, Serial No. 147,616

Term of patent 7 years

(Cl. D3—19)

To all whom it may concern:

Be it known that I, Clara E. McNutt, a citizen of the United States of America, residing at 3959 Revere Drive, Toledo 12, Ohio, have invented a new, original, and ornamental Design for a Thread Picking and Seam Ripping Implement, of which the following is a specification, reference being had to the accompanying drawing, forming part thereof.

Referring to the drawing:

Fig. 1 is a side elevational view of a thread picking and seam ripping implement in closed position showing my new design;

Fig. 2 is a distributed view of the device in open position;

Fig. 3 is a view on the line III—III, Fig. 2;

Fig. 4 is a view on the line IV—IV, Fig. 2; and

Fig. 5 is a view on the line V—V, Fig. 2.

I claim:

The ornamental design for a thread picking and seam ripping implement, substantially as shown.

CLARA E. McNUTT.
